UNITED STATES PATENT OFFICE.

GOTTLOB HONOLD, OF STUTTGART, GERMANY, ASSIGNOR TO THE FIRM OF ROBERT BOSCH, OF STUTTGART, GERMANY.

ARMATURE FOR MAGNETO-INDUCTION MACHINES.

1,072,228.

Specification of Letters Patent. Patented Sept. 2, 1913.

Original application filed October 4, 1909, Serial No. 520,931. Divided and this application filed October 14, 1911. Serial No. 854,894.

To all whom it may concern:

Be it known that I, GOTTLÖB HONOLD, a subject of the Emperor of Germany, and residing at Stuttgart, Germany, have invented certain new and useful Improvements in Armatures for Magneto-Induction Machines; and I do hereby declare the following to be a full, clear, and exact description of the invention, such as will enable others skilled in the art to which it appertains to make and use the same.

This invention relates to the construction of armatures or bobbins for magneto induction machines of the type usually known as "magnetos." In the usual construction of such machines the armature or bobbin is made up of a body portion carrying a winding in which the electromotive force is induced, and two head pieces which twice in each revolution, bridge across the space between the magnet poles and divert the lines of force from the path through the body of the bobbin and through the winding carried thereby. It is customary to support these bobbins for rotation in the magnetic field by means of two axle pins extending symmetrically from the body portion of the bobbins and suitably journaled in the frame of the machine. With such construction, it is impossible to slip a previously wound coil on the body or coil-carrying portion of a bobbin.

This application is a division of my co-pending application, Serial No. 520,931, filed October 4, 1909, which is intended to cover generically the broad idea of my invention, and specifically one particular form thereof in which the body portion is overhung by the head pieces. In that specific form a previously wound coil cannot be slipped on to the coil-carrying portion, although the coil may be wound on the body portion without interference by the axle pins.

In the particular modification constituting the invention covered by the present application, the head pieces merge into the body portion at one end without any overhang so that the coil may be entirely formed and then slipped in place on the body portion.

In the accompanying drawings illustrating my invention, Figure 1 is a view of a bobbin with the coil in place; Fig. 2 shows

a magneto with an armature similar to that of Fig. 1; Fig. 3 shows a modified form of bobbin; and Fig. 4 shows a magneto with an armature similar to that of Fig. 3.

In each of the drawings *a* is the body or coil-carrying portion of the bobbin, *b* and *c* are the head pieces and *d* and *e* are the axle pins. In Figs. 2 and 4, *f* indicates the magnet frame of an ordinary magneto, and *g* the pole pieces of the magneto frame, as is well known.

In all the figures the head pieces are flattened so as to have substantially the same thickness as the body portion *a*. The bobbins shown have a body or coil-carrying portion *a* and the head pieces *b* and *c* which carry the axle pins *d* and *e* at one extremity and at the other extremity merge into the body portion, that is without any overhang. By this construction, a previously wound coil may be slipped on to the body portion to the position shown. It is preferable to arch the coil-carrying part of the bobbin in order to more securely retain the coil in place. The axis of the body portion *a* may be at right angles to the axis of the axle pins *d*, *e*, as shown in Fig. 3, or these axes may be slightly different from this perpendicular arrangement, as shown in Fig. 1.

The armature including axle pins may be forged or pressed or otherwise formed of a single piece of metal, or the invention may be embodied in an armature made up of assembled parts, as will be readily understood.

If the armature is to be oscillated, in the well-known manner, by means of a cam and blade springs, then the cam may be formed directly upon the bobbin itself, as indicated at *k* in Fig. 1.

Having thus described my invention, what I claim is:

1. In a bobbin for magneto induction machines, a coil-carrying body portion, head pieces merging into the body portion at one end, and axle pins extending from the head pieces, whereby a previously wound coil may be slipped on to the body portion; substantially as described.

2. A bobbin for magneto induction machines having a coil-carrying body portion, head pieces merging into the body portion at one end, and axle pins extending from the head pieces, the body portion being convexed

to receive and retain a previously wound coil; substantially as described.

3. In a bobbin for magneto induction machines, a coil-carrying body portion, flat head pieces extending from the body portion, and axle pins extending from the head pieces, the axis of the body portion being angularly disposed with respect to the axis of the axle pins; substantially as described.
4. In a bobbin for magneto induction machines, a coil-carrying body portion having head pieces, and axle pins extending from the head pieces, the axis of the axle pins being substantially at right-angles to the axis of the body portion; substantially as described.

5. In a bobbin for magneto induction machines, a coil-carrying body portion, head pieces merging into the body portion at one

end, and axle pins extending from the head pieces, the axis of the body portion being angularly disposed with respect to the axis of the axle pins; substantially as described.

6. In a bobbin for magneto induction machines made from a single piece of metal, a coil-carrying body portion having head pieces which are flat on each side and of the same thickness as the body portion, and axle pins extending from the head pieces, the axis of the body portion being angularly disposed with respect to the axis of the axle pins; substantially as described.

In testimony whereof I affix my signature, in presence of two witnesses.

GOTTLOB HONOLD.

Witnesses:

REINHOLD ELWERT,
WALTHER STEINCKE.
